UNITED STATES PATENT OFFICE

2,200,611

LIGHTING FIXTURE

Wesley Wilson, Chicago, Ill., assignor to Wilson
Lighting Inc., Chicago, Ill., a corporation of
Illinois

Application July 29, 1937, Serial No. 156,274

1 Claim. (Cl. 240—103)

My invention relates to lighting fixtures.

One of the objects of my invention is to provide an improved reflector having a supporting flange portion lying in a plane at an oblique angle with respect to the axis of the reflector, the flange portion being formed integrally with the reflector portion.

A further object of my invention is to provide an improved method for forming such a reflector.

10 A further object of my invention is to provide such a construction in which the reflector and flange portion may be originally formed as surfaces of revolution so that the initial formation may be made by a spinning process.

15 Further objects and advantages of the invention will be apparent from the description and claim.

In the drawing, in which several embodiments of my invention are shown,—

20 Figure 1 is a side elevation showing a reflector before the flange portion has been deformed to give a tilt to the reflector;

Fig. 2 is an axial sectional view showing one method of deforming the flange to give a tilt to the reflector;

25 Fig. 3 is a section on the line 3—3 of Fig. 2 showing the reflector mounted;

Fig. 4 is an axial sectional view showing another form of reflector having a supporting flange portion lying in a plane oblique to the axis of the reflector;

Fig. 5 is a section on the line 5—5 of Fig. 4;

Fig. 6 is an axial sectional view showing another form of reflector;

30 Fig. 7 is a side elevational view showing a reflector with the supporting flange prior to deformation to secure the tilting of the reflector; and

Fig. 8 is an axial sectional view showing one method of deforming the flange of Fig. 7 to secure the tilting effect.

Referring to the drawing in detail, and first to Figs. 1 to 3, inclusive, the construction shown therein comprises a reflector 1 having a neck portion 2 to receive the neck of a lamp bulb and having a supporting flange portion 3 formed integrally with the reflector portion. Fig. 1 shows the reflector and flange prior to deformation of the flange. The structure shown in Fig. 1 may be formed by a spinning operation, as the parts shown are all surfaces of revolution about the axis of the reflector. In order to deform the flange 3, a tool and die construction may be used (as shown in Fig. 2), the tool member 4 having its lower edge inclined so as to press

downwardly an annular portion 5 of the sheet metal adjacent the juncture of the reflector portion 1 with the flange portion 3. The action is such that the line of juncture between the reflector portion and flange portion will finally lie in a plane nonparallel to and intersecting the plane of the outer edge of the flange so that when the reflector is installed in an opening 5a in the ceiling or the like, the axis of the reflector will be at an oblique angle to the plane 10 of the supporting edge of the flange portion 3. The terraced formation of the flange 3 lends itself readily to this distorting action.

In Figs. 4 and 5, the distortion to secure the desired tilting of the lamp is effected by deforming the terraced annular shoulder portion 6 between the neck 2 of the reflector and the reflector proper 1. The fixture may be formed in the first step of the forming process by a spinning process so that the shoulder connection portion 20 6 between the neck portion 2 and the reflector portion 1 will have a terrace-like formation which can be readily deformed so as to secure the desired tilt of the reflector portion with respect to the lamp supported by the neck portion. 25 This deforming action may be effected by a suitable tool 7 having annular edges 8 and 9 for engaging the terrace-like connection portion 6.

In Fig. 6 is shown a construction in which the connection 10 between the reflector portion 1 30 and the annular lamp supporting portion 11 in general may be crescent-shaped, the outer edge 12 of the crescent-like connecting portion lying in one plane, and the inner edge 13 of the crescent-like portion lying in another plane which 35 intersects the first plane substantially at the point 14.

In Figs. 7 and 8 is shown a different method of forming the supporting flange. In this form the reflector 1 and flange may be first formed as 40 shown in Fig. 7 so as to provide a substantially flat, outwardly-extending annular flange 15 which may be subsequently drawn or formed to the shape shown in Fig. 8. In this drawing process, the flange 15 may be held between 45 spring-pressed members 16 and 17, the spring pressure on the right-hand side being considerably greater than the spring pressure on the left-hand side so that when the tool 18 is forced downwardly, the right-hand edge of 50 the flange 15 will be firmly held while the left-hand edge will be drawn out from between the two gripping members 16 and 17, flowing down over the corner 19 of the lower gripping member, thus, in effect, increasing the 55

extent of one side of the reflector while leaving the other side of the reflector substantially the same length as in Fig. 7. In order to enable the tool 18 to follow the reflector downwardly without materially distorting it, the tool may be mounted for free self-adjusting movement.

Further modifications will be apparent to those skilled in the art, and it is desired, therefore, that the invention be limited only by the prior art and the scope of the appended claim.

Having thus described my invention, what I claim and desire to secure by Letters Patent is:

A sheet metal reflector comprising a concave reflector portion shaped as a surface of revolution and a circularly corrugated laterally extending supporting flange portion integral with said reflector portion and extending from the periphery thereof, shaped as a distorted surface of revolution, the different circular elements of said distorted surface of revolution lying in different nonparallel planes intersecting the reflecting surface of revolution.
